DESIGN FOR A PROJECTION LAMP

Henry M. Horldt, Detroit, Mich., assignor to
Brenkert Light Projection Company, Detroit,
Mich., a corporation of Michigan

Application July 5, 1938, Serial No. 78,259

Term of patent 14 years

To all whom it may concern:

Be it known that I, Henry M. Horldt, a citizen of the German Reich, residing at Detroit, in the county of Wayne and State of Michigan, have invented a new, original, and ornamental Design for a Projection Lamp, of which the following is a specification, reference being had to the accompanying drawing, forming part thereof.

Figure 1 is a perspective view of the projection lamp, showing the rear end and one side of my new design;

Figure 2 is a rear end view;

Figure 3 is a perspective view showing the front end and opposite side to that shown in Figure 1, and

Figure 4 is a front end view.

I claim:

The ornamental design for a projection lamp, as shown.

HENRY M. HORLDT.
